FIREARM

Elias I. Kelsey, Milford, Conn., assignor to Remington Arms Company, Inc., a corporation of Delaware

Application January 10, 1941, Serial No. 373,864

2 Claims. (Cl. 33—47)

This invention relates to gun barrels and particularly to a sighting rib for a shotgun barrel.

An important object of this invention is to provide an improved sighting rib for gun barrels. A further object is to provide a ventilated rib having one or more projections on its lower face and having a metal or plastic reinforcing piece. A still further object is to provide an improved method of securing a reinforced ventilated sighting rib to a gun barrel by projection welding.

There are at present two general methods of providing sighting ribs on gun barrels. These are namely: either by forming the rib as an integral part of the gun barrel during the construction of the latter, or by brazing or soldering the rib to the barrel. While the former method has the advantages of providing a rib which cannot be knocked or stripped off nor be twisted out of true, yet this method requires that the barrel be turned off center and then machined down so as to leave the upstanding rib. It is obvious that these steps are relatively expensive both from the point of view of time required and the material wasted in the machining process. The second method is likewise susceptible of improvement inasmuch as the union formed between the rib and the barrel by a brazing or soldering process is essentially a weak union and may be readily broken by an accidental blow or frequent jarring. Furthermore, the present methods of soldering, brazing or welding quite frequently effect burrs or disfigurement at the meeting edges of the component parts and often burn the metal or draw the temper so that parts are soft and easily bent and distorted. These disadvantages more than offset the advantages in forming the rib and barrel of separate pieces.

In the drawing:

Fig. 1 shows a profile of a gun having a ventilated sighting rib.

Fig. 2 shows an enlarged view of a sighting rib welded to a gun barrel.

Fig. 3 shows a cross section of the sighting rib on line 3—3 of Fig. 2.

Fig. 4 shows a cross section of the rib on line 4—4 of Fig. 2.

Referring to the drawing, the construction of the sighting rib is shown in Figs. 2, 3 and 4. In these drawings 10 represents the rifle barrel to which the sighting rib 11 is suitably secured. The latter comprises a relatively narrow strip of metal shaped in cross section substantially as an inverted truncated isosceles triangle and having a channel or groove formed in its bottom face 55

throughout its length as indicated at 12 in Fig. 3. The lower face of the rib, so formed, is adapted to be provided with one or more lateral cut-outs 13 as shown in Fig. 2, which not only effect a means for ventilating the rib but also form a plurality of legs or projections 14 adapted to contact the rifle barrel at spaced points. Inasmuch as these projections represent but a small portion of the area of the entire sighting rib and for the purpose of clarifying the discussion hereinafter as to the principles of projection welding, these legs or projections will be referred to as projections or legs of "restricted area." While the description of the rib 11, its groove 12, and cut-outs 13 has been limited to the figures shown in the drawings, it will be understood that modifications may be effected within the scope of this invention.

15 represents a longitudinal groove milled or otherwise formed in the channel portion 12 of the rib and adapted to receive the longitudinal edge 17 of a reinforcing piece 16. The primary purpose of the strip 16 is to act as a reinforcing rib between the barrel and the ventilated sighting rib to give strength and rigidity to the latter. In addition it may serve to keep dust and dirt out of the grooved rib and may add, in a measure, to the decorative appeal of the finished gun, particularly if formed of a colorful plastic. The opposite edge 18 of the piece 16, shown in cross section in Figs. 3 and 4, may be tapered so as to effect line contact on the surface of the barrel 10. The reinforcing piece 16 may be constructed of a suitable metal but in its preferred form a suitable plastic such as methyl methacrylate is used, molded or formed in some suitable shape and either translucent or colored for decorative purposes. It will be understood, however, that the invention is not limited to the use of methyl methacrylate but contemplates the use of such plastics as phenol-formaldehyde, cellulose acetate and other of the thermo-plastic and thermo-setting resins. The reinforcing strip 16 is suitably secured within the groove 15 of the sighting rib by means of a compatible adhesive, a solder or simply by a tight machine fit, the method employed being determined by the kinds of materials used. The rib, including its reinforcing strip, is properly oriented on the upper side of the gun barrel and secured thereon by a process of projection welding.

In carrying out the welding operation, the legs or projections 14 are temporarily held in proper position on the gun barrel as by suitable pressure applying means; thereafter a pair of

suitable electrodes are placed one in electrical contact with the barrel 10 and the other in electrical contact with the sighting rib 11 and sufficient electric current passed through the assembled parts and projections to heat the parts to a welding temperature. While at the welding temperature, and after discontinuance of the heating current, a suitable amount of pressure is maintained on the component parts for a sufficient period to effect the welding of the several projections to adjacent points on the barrel without the usual arcing or the formation of burrs. This method of welding is thus characterized by the principle that the projections 14 of restricted area localize the flow of heating electric current and as a result a high electrical resistance is set up at each area, the effect of which is to develop a welding temperature at each projection in a relatively short time. The adaptation of this characteristic or projection welding to the art of gun manufacture and in particular to a method of securing the sighting rib to the barrel is a practical solution of an inexpensive method of assembling such component parts without the hazards of disfiguring, burring and warping the barrel or rib due to maintaining prolonged high temperatures over relatively large contacting areas. In accordance with the present invention the projections 14 on the sighting rib 11 are heated sufficiently and suitable pressure applied to produce a weld of the adjoining and contacting portions thereof yet the barrel 10 is not subjected, during the relatively short heating period, to such degree of heat as is likely to draw the temper of the barrel or soften or anneal it so that the same would be likely to easily be bent or distorted from its normal alignment. It may fairly be said, therefore, that the invention represents an improved method of securing a sighting rib to a barrel characterized by an unexpected result in that in ordinary soldering, brazing or welding processes the adjacent parts to the weld are usually heated to temper and finish destroying temperatures whereas in the present case the improved method of welding leaves the barrel of the gun comparatively cool in the vicinity of the weld whereby its temper and finish are

not destroyed. Furthermore, the idea of using projections of restricted area permits the use, in any well-known manner, of large flat-surfaced electrodes, avoiding the possibility of marring the surfaces of the sight or barrel during welding which may be occasioned by the use of pointed electrodes or soldering or brazing tools.

To recapitulate, the present invention introduces a new and practical method of securing 10 an improved sighting rib to a gun barrel. The sighting rib is formed with one or more projections of restricted area on its lower face which offer great resistance to the flow of electricity and hence develop welding heats over the restricted areas in a relatively short period and at a minimum current output. These high welding heats are distributed at spaced points 15 of the rib and barrel and hence the parts, as a whole, are not subjected to such degree of heat as would be likely to cause warping or destruction of their normal alignment and finish when subjected to suitable welding pressures. In addition the improved rib is further characterized by a reinforcing piece made of metal or suitable 20 plastic which not only protects the accuracy of the sighting rib against accidental knocks, vibrations, etc. but in addition permits the shock-proof rib to be ventilated without loss of its strength or rigidity. It will be appreciated also 25 that if a plastic reinforcing piece is used its color and pattern may be varied to add considerable decorative value to the gun.

What is claimed is:

1. A sighting rib for gun barrels comprising a 30 strip of metal having an upper sighting surface and provided on its lower surface with spaced projections of restricted area adapted to form welding contacts for uniting the rib to the barrel, and having a reinforcing insert between said 35 projections.

2. A sighting rib for gun barrels comprising a strip of metal having an upper sighting surface, provided on its lower surface with a plurality of 40 projections of restricted area adapted to form projection welding contacts for uniting the rib to the barrel and having a plastic reinforcing insert between said projections.

ELIAS I. KELSEY.
